UNITED STATES PATENT OFFICE.

FREDERICK A. VOOS, OF NEWARK, NEW JERSEY, ASSIGNOR TO WESTERN ELECTRIC COMPANY, INCORPORATED, OF NEW YORK, N. Y., A CORPORATION OF NEW YORK.

VACUUM-CLEANER ATTACHMENT.

Application filed July 3, 1924. Serial No. 724,090.

This invention relates to vacuum cleaner attachments and more particularly to vacuum cleaner attachments for cleaning slotted surfaces wherein particles of metal or other matter collect and solidify. The invention relates more specifically to a vacuum cleaner attachment for cleaning a slotted cylindrical surface such as an interrupter drum used in automatic telephone exchange systems but it is to be understood that the invention in a modified form may be used for cleaning any surface requiring a combined brushing and suction action.

The object of the invention is to provide improved facilities for cleaning slotted surfaces and particularly the drums of electrical interrupters.

This object is attained by the provision of a vacuum cleaner attachment for setting up a combined brushing and suction action, having a nozzle the contact edge of which is shaped to conform to the general shape of the surface to be cleaned and a brush adjustably mounted within the nozzle adapted to be adjusted to variably project the brushing surface of the brush beyond the rim of the nozzle and to compensate for wear on the brushing surface.

Fig. 1 is a longitudinal view partly in cross-section of the vacuum cleaner attachment attached to the hose of a vacuum cleaner with the nozzle thereof applied to a slotted cylinder which it is desired to clean.

Fig. 2 represents a cross sectional view along the line 2—2 of Fig. 1 showing the manner in which the brush is adjustably held within the nozzle.

Fig. 3 is a longitudinal view of a modified form of vacuum cleaner attachment shown partly in cross-section, for cleaning a flat slotted surface.

The attachment consists of a tube 4 of fibre or other insulating material, one end of which is arranged to be fitted over the hose of a vacuum cleaner. The other end known as the nozzle is shaped so that its contact edge conforms to the general shape of the surface to which the attachment is to be applied, as illustrated in Figure 1 or 3. Mounted within the tube is a stud 8, having one end threaded and reduced in

cross-section and extending through a hole drilled through the wall of the tube. A washer 9, whose underside conforms to the outer cylindrical surface of the tube is placed over the reduced end of the stud and a check nut 11 is then screwed on the threaded end of the stud for securely fastening the stud to the tube. A hole 12, serving as a bearing for the brush handle 6, is drilled through the stud 8, in a line parallel or coincident with the axis of the tube.

Mounted within the hole 12 of the stud 8 is a brush 7 the bristles of which are secured in the twisted wire handle 6. For adjustably securing the brush handle in the hole 12 the stud 8 is provided with an axial threaded opening leading into the hole 12, into which opening a set screw 10 is screwed to press the brush handle 6 against the surface of the hole 12.

When the attachment is to be employed in cleaning a cylindrical surface, the bristles of the brush 7 are trimmed to conform to the general shape of the nozzle in order to prevent the bristles from being bent and broken. In cleaning an object having a slotted surface such as the interrupter drum 5, the brush is adjusted to project beyond the rim of the nozzle so as to enter into the slots as the nozzle is moved along the line of the slots 2 therein.

By unscrewing the set-screw 10, thereby loosening the brush handle 6, the brush may be adjusted to brush out slots of various depths and to compensate for wear on the bristles of the brush.

What is claimed is:

A vacuum cleaner for cleaning slotted interrupter drums comprising a tube of insulating material for attachment to the hose of a vacuum cleaner, said tube having a contact edge curved to fit the curve of the drum to be cleaned, a brush axially mounted within said tube, projecting beyond said contact edge, and means comprising a screw projecting through the side of the tube and engaging the brush handle for determining the distance the brush projects beyond the contact edge.

In witness whereof, I hereunto subscribe my name this 27th day of June, A. D. 1924.

FREDERICK A. VOOS.
